UNITED STATES PATENT OFFICE.

GOTTLOB KLUMPP AND HENRY FELIX HERMAN, OF BROOKLYN, NEW YORK; SAID HERMAN ASSIGNOR TO SAID KLUMPP.

INCANDESCENT LAMP.

No. 830,598.

Specification of Letters Patent.

Patented Sept. 11, 1906.

Application filed September 9, 1905. Serial No. 277,739.

To all whom it may concern:

Be it known that we, GOTTLÖB KLUMPP, a subject of the German Emperor, and HENRY FELIX HERMAN, a citizen of the United States, residents of Brooklyn, in the county of Kings and State of New York, have invented a new and useful Improvement in Incandescent Lamps, of which the following is a specification.

10 This invention relates to certain new and useful improvements in incandescent electric lamps, and has particular reference to that class in which a light of varied intensity may be obtained and to what is commonly known 15 upon the market as "high and low".

The objects of the invention are to provide a cheap, simple, and durable construction in which only one contact and one filament is employed, together with certain means which 20 are arranged for engaging with the contact and by the adjustment of which a light of varied intensity may be obtained or the light entirely extinguished, as occasion may necessitate.

25 Further objects of the invention are to provide a construction capable of attachment to the ordinary make of sockets, one in which the light may be raised or lowered or completely cut off by manipulating the globe, and 30 also one that will be neat in appearance and of such design that its connection to the socket will not interfere with the attachment of the ordinary construction of globes or shades.

35 With these briefly-stated objects in view the invention comprises certain details of construction and peculiar combinations and arrangement of parts, as will be fully described in the following specification and pointed 40 out in the claims; reference being had to the drawings, in which—

Figure 1 is a perspective view of my improvement, showing a lamp applied thereto. Fig. 2 is an enlarged vertical sectional view 45 of the same, the lamp being shown in elevation. Fig. 3 is an enlarged horizontal sectional view drawn on the line 3-3 of Fig. 2 and looking in the direction indicated by the arrow. Fig. 4 is a similar view drawn on the line 4-4 of Fig. 2 and showing the trolley member in elevation. Fig. 5 is a section on the line 5-5 of Fig. 2. Fig. 6 is a detail perspective view of the bridge. Fig. 7 is a detail perspective view of the disk. Figs. 8 and 9

are detail perspective views of the trolley member, and Fig. 10 is a detail plan view of the blank form from which the trolley member is made, and Fig. 11 is a detail perspective view of the spring contact-plate.

In the drawings, A designates the plug 60 comprising an outer threaded sleeve A', in which fits a threaded U-shaped member A'', which I shall hereinafter refer to as a "bridge." Against the top of the bridge it fitted a fiber disk A'', whose periphery is surrounded by 65 the upper edge of the sleeve, which also extends over the edge of the disk, as shown most clearly in Fig. 2 of the drawings. At the lower end of the plug is held a pair of clamping-disks B and B', of fiber or other 70 non-conducting material, between which is clamped the top plate C of the shell or casing C', which incloses the operating parts of the device, as will be fully explained later on.

A rod or post D passes through the plug 75 and disks and serves to securely lock them together, the said rod having a nut threaded upon its upper end which rests against the fiber disk A'' and is adapted to engage the usual spring-finger of the socket. Upon the 80 lower end of the rod or post is held a plate or disk E, of slate or other non-conducting material, which is held adjacent the lower clamping-disk B' and spaced therefrom by a fiber washer D'. Upon its lower face and near its 85 periphery the plate or disk E is provided with a circular groove E', in which is placed and held a strip E'' of any suitably high resistance material. This strip extends around the groove for the greater portion of its 90 length; but the ends are spaced some distance apart, so that an open space is provided, so that the wheel may be entirely disengaged from the strip and the current cut off. One end of the strip E'' is engaged by a plate G', to 95 which is connected a conductor-post G, which extends up through the plate or disk E and clamping-disks B and B' into the socket and has its upper end connected to a foot portion a of the bridge A''.

The casing or shell C' is connected to the plate C in any suitable manner and its lower end is bent inwardly for a short distance to provide a flange C'', the inner edge of which rests within a groove or raceway formed between collars H and H', which are threaded upon a socket I, into which the base J of the lamp J' is screwed. This arrangement se- 100 105

curely holds the lamp and socket to the shell, but permits of them being easily revolved.

The upper end of the socket I is turned inwardly to provide an annular flange or open head I', upon which is held a trolley member K, which is clamped in position by washers L and L', of fiber or other non-conducting material, that are clamped above and below the head of the socket by a screw-post M, having a head upon its lower end and a nut threaded upon its upper end and between which the washers and trolley member are clamped to the socket I. The post M is engaged at its lower end by the contact-plate J³ of the lamp and at its upper end by a spring contact-plate N, securely held upon the post D between its head and the lower face of the disk E.

The trolley member is of a peculiar construction and is formed of a single piece of spring metal bent to provide a base K', from which projects an arm K'', whose extreme end is reduced in width and bent downwardly and upwardly, as shown at K³, to provide vertical portions which form bearings for a shaft upon which is held a trolley-wheel K⁴, that forms a contact and is designed for engagement with the plate or disk E and strip E', carried within the groove E'. The central portions of the base K' and arm K'' of the trolley member is cut out, providing an opening through which the contact-plate N and the post M may pass, and these openings are of the size to prevent engagement by either the plate or post.

When the various parts are assembled, as shown in Fig. 2 of the drawings, it will be readily understood that the current from one of the line-wires will pass down the post D, through the contact-plate N, the post M, to the contact-plate J³ of the lamp, through the filaments of the lamp, and thence up through the socket I, trolley member K, trolley-wheel K⁴, the strip of high-resistance material E', post G, bridge A², and finally through the sleeve A', thus forming a complete circuit.

It is well known that in the use of any high-resistance material for conducting a current of electricity the farther one point of contact is arranged from the other point the weaker or lighter the current will be, likewise the nearer one point of contact is arranged to the opposite point of contact the stronger the current will be. This same principle is carried out in the construction of my device by the use of the strip of high-resistance material, and it will therefore be readily seen that the farther the trolley K is moved from the post G the weaker will be the current which is conducted to the filament, and therefore the dimmer will be the rays of light emitting therefrom.

In the operation of my device it will be seen that by simply revolving the bulb axially the socket and trolley will also turn and

cause the wheel K⁴ to be moved around the surface of the strip E', and should a bright light be desired the trolley is moved until it is arranged immediately adjacent the post G, when a direct current will pass through the various parts; but should the bulb be turned so that the trolley-wheel will be held in contact with the strip at the farthest point from the post G an extremely weak current will be produced, and in consequence a dim light. If it should be desired to entirely extinguish the light, the bulb is further revolved until the trolley passes either end of the strip E', when it will engage the plate or disk E and the current will be completely cut off. It will thus be seen that by simply revolving the bulb the light may be raised or lowered or completely cut off, and by the arrangement of the trolley and its support and the manner of holding the socket and its connected parts to the casing the socket may be easily revolved and the trolley readily moved around the strip E, the light adjusted gradually, and the "jumps" common in devices of a similar character are positively avoided. Of course it will be understood that should it be desired to lower or completely turn the light out after it has been burning at its highest for any length of time and the bulb should become hot it may be readily accomplished by catching hold of the collar H', and by simply revolving it the socket and its connected parts may be easily revolved the same as if the bulb was operated.

Having thus fully described our invention, what we claim as new, and desire to secure by Letters Patent, is—

1. A device of the kind described comprising a contact-strip of high resistance, a rotatable lamp-socket, an electric circuit including said contact-strip, and a contact carried by the socket and adapted to travel upon the said contact-strip, said contact being also in the circuit.

2. A device of the kind described, a contact-strip, a rotatable lamp-socket, an electric circuit including said contact-strip, and a wheel carried by the socket and adapted to travel upon the contact-strip, said wheel being also in the circuit.

3. A device of the kind described, comprising a disk of insulating material, a path formed of a conducting material of high resistance arranged upon said disk, a rotatable lamp-socket, means for holding the said socket adjacent the disk, and a wheel carried by the socket and adapted to travel upon the path of the conducting material when the socket is rotated.

4. A device of the kind described, comprising a contact-strip having a high resistance, the ends of the strip being insulated from each other, an electrical circuit connecting with one end of said strip, a rotatable lamp-socket, a trolley carried by the lamp-socket,

and a trolley-wheel carried by the trolley and adapted to travel upon the contact-strip and the insulating material and to move toward or away from the electrically-connected end 5 of the contact-strip when the lamp-socket is rotated.

5. A device of the kind described, comprising a disk of insulating material, a non-continuous contact-strip arranged upon said 10 disk, a conductor-post passing through the disk and engaging an end portion of the contact-strip, a rotatable lamp-socket, a spring-metal trolley carried by the socket and a wheel carried by the trolley adapted to travel 15 in a path including the contact-strip.

6. A device of the kind described, comprising a plate of insulating material, a divided contact-strip substantially circular in form and of high resistance embedded in one face 20 of said plate, means for rotatably holding a lamp-socket adjacent the said plate, a lamp-socket rotatably held by said means, a trolley carried by the lamp-socket and a wheel carried by the trolley and adapted to travel 25 upon the contact-strip and plate when the lamp-socket is rotated.

7. A device of the kind described, comprising a plate of non-conducting material, a conductor passing through said plate, a strip 30 of contacting material of high resistance car-

ried by the plate, a conductor-post passing through the said plate and in contact with an end of said strip, a lamp-socket rotatably held adjacent the plate, means for electrically connecting the said socket with the conductor first mentioned, and a spring-pressed trolley-wheel carried by the socket and included in the circuit, said trolley-wheel being adapted to rest upon the contact-strip and upon the plate between the ends of the strip and to 35 travel from the free end of the strip to a point adjacent the second-mentioned conductor-post.

8. The combination with a rotatable lamp-socket, of a plate of non-conducting material, 40 a contact-strip carried by said plate, a trolley carried by the lamp-socket, said trolley being formed of spring metal bent to provide a base adapted to rest upon the lamp-socket and having a spring-arm integral with the base, 45 the extreme end of the arm being bent downwardly and upwardly to form a bearing and a trolley-wheel held in said bearing and adapted to travel upon the plate and contact-strip.
